UNITED STATES PATENT OFFICE

FRIEDRICH WAGNER, OF RUSSDORF, NEAR OBERFROHNA, GERMANY

DOUBLE WARP FRAME

Application filed January 15, 1929, Serial No. 332,594, and in Germany January 23, 1928.

The present invention relates to a double warp frame provided with withdrawable sinkers and adapted to produce double-sided goods.

5 In the known types of double warp frames the old loops land on the spring needles, which have been previously compressed by the presser bar, with the aid of sinkers arranged between the needles. In order to 10 place the leases or laps on the spring needles, the latter must be long enough and pushed up high enough between the sinkers to insure safe landing of the new laps under the hook of the needles, and this position determines 15 the length of the needles. Even in cases where the sinkers were temporarily moved out of range of the needles, it was done during another phase of the working rhythm when shortening of the needles was not possible.

The present invention eliminates these drawbacks and enables operators to keep the needles as short as is consistent with lapping. I attain this object by withdrawing the sinkers or web-holders from the row of needles before lapping takes place so that the leases can be placed on the full length of the needle. During the pressing step and the landing of the loops the entire length of the needles is 30 no longer required so that the sinkers can be pushed back between the needles for the knocking over and locking in process. My invention permits shortening of the needles for the width of the sinkers, which increases 35 materially the rigidity of the needles and reduces their wear and tear.

The invention is illustrated in the accompanying drawing, in which Figs. 1 to 4 show diagrammatically the operation of the new machine provided with short needles. Figure 1 shows the knocking over of a row of loops; Fig. 2 shows the phase in the knitting operation when the sinkers retract after having performed the knocking over operation and preparatory for the yarn guides to lap; Fig. 3 shows the position of the parts after lapping; and Fig. 4 shows the pressing of the needles. In Fig. 1 the sinkers 1 are within the range of the needles for the purpose of locking in the loops. As soon as the

threads 2—3 are to be placed on the needles 4, the sinkers or web-holders 1 move back (Fig. 2) so that they are withdrawn completely during lapping (Fig. 3) and the last-formed loops are held by the non-working needles of the other row without having an opportunity of shifting relative to the stem of the working needles.

The needles are of such a length as to permit lapping when the sinkers are retracted from the needles and are of insufficient additional length to permit lapping when the sinkers are advanced, and furthermore during the laying of the threads the fabric is held tight by the other row of needles near the securing parts of the needles so that it cannot be drawn up to the needle hook upon these needles.

I claim:—

A double warp frame comprising two banks of needles and two banks of sinkers, each of said banks of sinkers cooperating with and encroaching temporarily in one of the rows of said needles, said sinkers adapted to be withdrawn from its corresponding row of needles when lapping takes place, said needles being of such a length as to permit lapping when the sinkers are retracted from the needles and being of insufficient additional length to permit lapping when the sinkers are advanced, and during the laying of the threads the fabric is held tight by the other row of needles near the securing parts of the needles so that it cannot be drawn up to the needle hook upon these needles.

In testimony whereof I have affixed my signature.

FRIEDRICH WAGNER.
